BURNER

Eugene A. Rowe, Seattle, Wash., and Percy M. Forster, Berkeley, Calif., assignors to Standard Oil Company of California, San Francisco, Calif., a corporation of Delaware

Application March 14, 1932, Serial No. 598,688

6 Claims. (Cl. 158—106)

This invention relates to gas burners or torches and is particularly directed to portable burners such as are used in pre-heating metal parts to be welded, heating rivets, annealing castings and welded objects, expanding hubs and wheels preliminary to shrinking them on shafts, and work of similar nature. It is particularly adapted for use with liquefied petroleum gas such as propane, butane, and the like, and in combination with a cylinder or bottle of such liquefied gas constitutes an efficient and readily portable heater. An object of this invention is to provide a burner of the air induction type in which a source of compressed air is not required for efficient combustion and the production of intense and localized heat.

Another object is to provide a torch or burner in which the source of primary air may be controlled and adjusted to suit the conditions of gas pressure and flame size required. Another object is to provide a torch which will direct a relatively small diameter cylinder of flame so that its disposition may be readily controlled.

25 A further object is to provide a burner construction which will be simple, economical and easy to manufacture and in which adjustments for flame size and gas consumption may be readily made.

30 Various other objects and advantages will be more fully apparent from the following description and drawing which illustrate a preferred embodiment of this invention.

The customary form of torch or burner of this nature and heating capacity for use with illuminating or natural gas under low pressure must be provided with compressed air in order to supply sufficient oxygen for complete combustion of the gas. It is not always convenient or economical to provide a source of compressed air for a burner, particularly in small shops, or in remote localities such as logging camps, on board ships, etc.

Because of the fact that the pressure available from natural or artificial gas mains is on the order of a few ounces or at the most, 1 or 2 pounds per square inch, the construction of small so-called air-induction burners is such that they are not suitable for use with gas of higher pressure, such as the newly introduced bottled or liquefied petroleum gas. Most of these burners are of the customary Bunsen type in which the gas emerges from a small orifice or nozzle and is directed into the center of a single large diameter Venturi tube or its equivalent. The aspirating

effect of the gas is used to draw in as much air as possible through the large flared inlet end of the Venturi tube. No provision is made for the introduction of secondary air, which has been found essential to secure complete and efficient combustion in large torches, with high heat value gas under high pressure.

In other words, conventional burners larger than the customary laboratory type, which are of the construction suitable for natural or artificial gas of low heat value, are not adapted to be used with liquefied petroleum gas. Elaborate and comprehensive tests with all commercial burners available showed them to be unsuited to this fuel. Therefore, it is evident from the subjoined drawing and description that the burner of the present invention is a radical departure of the general type of air-induction burners and that its novel feature is a primary or premixing tube of very small diameter as compared with the main body 10 of the burner, in which the rapidly moving jet of gas inspires and mixes with the primary air for combustion. Secondary air is admitted to this mixture through holes in the outer casing of the burner and a completely balanced and intensely hot flame is produced at the tip of the torch.

The accompanying drawing shows a partial sectional view of a torch or burner embodying the essential features of this invention.

In this drawing, 1 represents the outer tube or body of the burner, which is preferably made of cast bronze or other material which will resist oxidation, as it may be intensely heated for about $\frac{1}{3}$ of its length. The tube 1 is preferably reduced 35 to a somewhat smaller diameter at its outermost end as at 2, in order to contract the flame and prevent its assuming a diverging conical shape. Secondary air ports are provided as at 3 and are preferably symmetrically arranged around the circumference of the tube or body 1. The rear end of the tube or body 1 is closed as shown at 4 and constitutes a support for the brass primary air mixing tube 5 which is screwed or brazed 40 in place. It is essential that the tube 5 be concentric with the tube or body 1.

Two arms 6 extend from the back of the body 1 and terminate in an annular boss or sleeve 7, which is drilled and threaded concentric with the tube 5. Adjustably mounted within the annular boss 7 is a brass gas supply pipe 8, which is threaded for a portion of its length as at 9 and which extends completely through the boss 7 into the space between the arms 6. A threaded 45

lock nut 10 is provided to secure the adjustment of the pipe 8 with respect to the boss 7.

An internally threaded brass cap 11 is mounted on the inner end of the pipe 8 and is drilled as at 12 to provide a single small diameter orifice through which the gas flows and enters the tube 5, as a high velocity jet.

Threads 13 are provided at the outer end of the pipe 8 and a conventional gas throttling needle valve 14 is screwed thereon. A flexible hose (not shown) leads from the coupling 15 of the valve 14 to the pressure regulator of the tank or bottle of liquefied petroleum gas (not shown).

It is apparent that the amount of primary air aspirated may be varied as desired by loosening the lock nut 10 and screwing the threaded portion 9 of the gas supply pipe 8 in or out of the threaded boss 7, thereby changing the distance between the tip of the gas orifice cap 11 and the inlet end of the mixing tube 5. The size of the flame and the rate of gas consumption may be altered by substituting tips having various size orifices. If but one rate of gas combustion is desired the end of the pipe 8 may be swaged or brazed shut and an orifice drilled directly therein, care being taken to insure that it is concentric with the tube 5. The length of the tube 5 and the number and location of the secondary air ports 3, however, need not be changed for any particular burner.

The primary air mixing tube 5 is preferably supplied with slots 16 spaced around its circumference and extending back a short distance from the outlet end. Other forms of openings may serve the same purpose but for convenience and simplicity the use of slots cut by means of a hack saw at 90 degree intervals is preferred.

It is not known exactly the theory on which these slots perform their desirable function which appears to result from a degree of turbulence set up between the primary air gas mixture and the secondary air, but in any event it has been found that the slotted tube causes the flame to burn farther back in the outer tube or body 1 and prevents the flame from blowing out even under materially increased gas pressures.

As an example of this invention a torch was constructed with an outer tube or body 1, which was of $\frac{1}{8}$ inch thick material, 2 inches inside diameter and 5 inches long, with an inner mixing tube $\frac{5}{8}$ inch inside diameter and $1\frac{1}{8}$ inches long, provided with 4 slots 16 approximately $\frac{1}{8}$ inch wide and $\frac{1}{2}$ inch deep. Twelve secondary air ports 3 were located as follows: Two were diametrically opposite and $1\frac{1}{2}$ inches from the end of the burner, four were 90° apart around the circumference and $2\frac{1}{4}$ inches from the end of the burner, four were similarly located $3\frac{3}{8}$ inches from the end of the burner, and two were diametrically opposite and 4 inches from the end of the burner.

The tip of the burner tube or body 1 was reduced to $1\frac{1}{8}$ inches inside diameter at 2. The gas orifice tip 11 was drilled with a $\frac{1}{8}$ inch diameter hole and was located $\frac{1}{2}$ inch from the face of the closure 4. With these proportions and a pressure of 20 pounds per square inch of propane gas, approximately 4 pounds per hour of liquid propane were consumed. As liquefied propane weighs approximately 4.45 pounds per gallon and 1 gallon will vaporize to approximately 38 cu. ft. of gas at atmospheric pressure and temperature, which gas has a heat value of approximately 2,500 B. t. u.'s per cu. ft., a total heat output of approximately 85,000 B. t. u. per hour was

obtained with perfect combustion. It was also found that a reduction in pressure to approximately 5 pounds per square inch on the propane gas supply still resulted in an apparently perfect mixture and gave a smaller but intensely hot blue flame.

It will be apparent that a number of modifications and changes could be made in this arrangement without departing from the essential feature of the invention which embraces all changes, variations, and substitutions coming within the scope of the appended claims.

We claim:

1. In a burner for hydrocarbon gas, a cylindrical primary mixing tube of small diameter, a secondary tube surrounding the primary tube and provided with a plurality of radial secondary air ports near its outlet end, closure means for the said secondary tube maintaining the tubes in their respective positions, a bifurcated extension to said secondary tube terminating in an annular boss, an adjustable conduit secured in said boss, said conduit terminating in a closure provided with a small diameter orifice and adapted to direct a jet of gas at high velocity into the primary tube thereby inspirating primary atmospheric air into said tube with the gas.

2. In a burner for burning inflammable gas with atmospheric air, a hollow cylindrical body closed at one end, and having ports in its cylindrical wall near its outlet end, a tube inserted in the closed end of said cylindrical body concentric therewith and providing a passage therethrough, said tube extending into said cylindrical body for a portion of the latter's length and having slots in its outlet end, and means for introducing a jet of gas to said tube whereby a mixture of gas and air is drawn into said passage and burns as an axial flame at the outer end of said cylindrical body.

3. A burner for hydrocarbon gas comprising a hollow cylindrical member with a closed end, an orifice in said closed end, a tube inserted in said orifice and extending into said cylindrical member, said tube having slots through its wall adjacent its inner end, and means for directing a jet of gas into said tube whereby a mixture of gas and air is drawn into said tube so as to burn at the open end of said cylindrical member.

4. A burner for inflammable gas comprising a hollow cylindrical member with a closed end, ports in the cylindrical wall of said member, an orifice in the closed end of said member, a tube inserted in said orifice and extending into said member, said tube having slots through its wall, a gas supply line terminating in a jet orifice directed toward the orifice in the said cylindrical member and in spaced relationship thereto, and means for adjusting said spaced relationship.

5. A burner comprising a hollow cylindrical member having one end closed, a substantially straight, small diameter primary air mixing tube extending into the closed end of said cylindrical member, means adjacent the inlet of said tube for injecting a high pressure jet of air-inspirating gas therethrough, and ports through the wall of said cylindrical member adjacent the end of said tube and adapted to admit secondary air radially to the air-gas mixture issuing from said mixing tube, the resulting mixture burning as an axial flame at the open end of said cylindrical member.

6. A burner for high pressure hydrocarbon gas

comprising a hollow cylindrical member with a closed end, an orifice in said closed end, a small diameter tube seated in said orifice and extending inwardly into said cylindrical member, said member provided with ports intermediate its ends, and means for directing a jet of high pressure

gas through said tube, whereby atmospheric air is drawn into said tube and mixed with said gas so as to burn at the open end of said cylindrical member.
